IMPROVEMENT IN HARNESS SADDLES.

JOHN FYE, OF HAMILTON, OHIO.

Letters Patent No. 60,168, dated December 4, 1866.

SPECIFICATION.

TO ALL WHOM IT MAY CONCERN:

Be it known that I, JOHN FYE, of Hamilton, in Butler county, in the State of Ohio, have invented a new and useful Improvement in Harness Saddles; and I do hereby declare that the following is a full and exact description thereof, reference being had to the accompanying drawings, and to the letters of reference marked thereon.

Figure 1 of the drawings represents the saddle-tree, with the turrets and water-hook detached.

Figure 2 represents the water-hook detached.

Figure 3 represents one of the turrets detached, with one-half of its convex bisected base attached thereto.

My invention relates to the means of attaching the turrets, and water-hook, and crupper-loop to the saddle-tree, and to the manner of constructing the several parts and combining them, as will be herein fully described. My saddle-tree may be made of any suitable material, or cast of any of the different kinds of metal. The furnishings, viz., turrets, hook, and loop may also be made of cast malleable iron or other metal.

In the accompanying drawings, A denotes the saddle-tree; B the crupper-loop; C is the square opening through which the water-hook is inserted; D D designate the two half-bases by which the turrets are supported in position; S S denote the saddle of the water-hook, which is provided with three screw-holes to hold it firmly by means of screws to the saddle-tree. The turret-bases are constructed with dovetail-shaped rebates, which furnish sockets for the correspondingly formed feet of the turrets, the said feet being designated by the letters m m. The crupper-loop is formed with a screw, so as to be inserted or replaced, when broken off, without ripping open the saddle-pad, as has been necessary when this loop is riveted to the tree. The inside, or under side of my improved saddle-tree is made plain, that is, without projections for the purpose of securing the turrets and water-hook, as heretofore. The turrets may also be secured in place without interfering with the leather or other parts of the saddle, or its workmanship. One-half of each of the bases, with its rebate for the turret, is to be cast with the tree, as represented in fig. 1, and the turrets may be cast in connection with the other half of the convex rebated base; or these may be cast separately, and in either case the half of the rebated base must be provided with a screw-hole for the screw, to secure it to the saddle-tree. On the under side of the centre of the front of the saddle-tree, there are two projections for the purpose of sustaining the position of the water-hook, which is to be inserted from the top or upper side of the saddle-tree, so as to bring its saddle, S S, down upon the tree. The two projections under the front will not be made to extend or project below that portion of the water-hook which lies between them, when in its place. The saddle may be constructed upon my improved saddle-tree without inserting either the water-hook, turrets, or crupper-loop, and after it is completed by the workman, these parts may be secured in their place with great facility, and in a firm and secure manner. To insert and secure the water-hook in place, after the saddle is finished, the point of the hook will be inserted and the hook drawn through until it brings the saddle, S S, to its seat upon the tree, when three screws are inserted which retain it in place. To secure the turrets in place, the feet, m m, of dove-tail form, are placed in their corresponding sockets in the base-pieces D D, when the other half of each of the convex bisected bases are brought into position and fastened with screws, as represented. The crupper-loop is attached, as heretofore described, by means of a screw-thread thereon. My improved detachable turrets, with their bases, and the water-hook, may be secured to saddle-trees of any form or construction.

Having now fully described my improved harness saddle-tree, what I claim therein, and desire to secure by Letters Patent, is—

1. The combination of the detachable bisected bases, with dovetailed rebates therein, with the turret-feet m m, and saddle-tree, when constructed and secured together in the manner and for the purpose specified.
2. I claim the detachable water-hook, with its saddle S S, in combination with the saddle-tree, when constructed and applied in the manner described.
3. I claim the turrets, with their bases, and the water-hook, with its saddle, in combination with the crupper-loop, and saddle-tree, when the several parts are constructed and secured together in the manner and for the purposes set forth.

JOHN FYE.
